UNITED STATES PATENT OFFICE.

ROBERT FISCHER, OF NEW YORK, N. Y.

PIN-RETAINING DEVICE.

No. 844,274.

Specification of Letters Patent.

Patented Feb. 12, 1907.

Application filed February 24, 1906. Serial No. 302,730.

To all whom it may concern:

Be it known that I, ROBERT FISCHER, a citizen of the United States, and a resident of the city of New York, borough of Brooklyn, 5 in the county of Kings and State of New York, have invented a new and Improved Pin-Retaining Device, of which the following is a full, clear, and exact description.

The purpose of the invention is to provide 10 a very simple, economic, and effective device for holding a pin in the position in which it may be placed in a fabric or garment until purposely removed by the wearer or other 15 authorized person and to so construct the device that it will be light, simple, strong, and easily operated to lock the pin or release it.

The invention consists in the novel construction and combination of the several parts, as will be hereinafter fully set forth, 20 and pointed out in the claim.

Reference is to be had to the accompanying drawings, forming a part of this specification, in which similar characters of reference indicate corresponding parts in all the figures.

25 Figure 1 is a perspective view of the device in locked position on a pin. Fig. 2 is a longitudinal section through the device, drawn upon an enlarged scale, showing a portion of a pin therein in dotted lines. Fig. 3 is a 30 transverse section taken practically on the line 3-3 of Fig. 2; and Fig. 4 is a vertical section through the device, showing the two main portions thereof partially separated.

The device is made in two sections A and B, 35 suitably connected, the section A being that which receives the pin, and the section B that which contains the locking mechanism for the pin. Both sections are constructed of thin sheet metal and are preferably substantially U-shaped in cross-section.

40 The outer longitudinal edge portion 11 of the pin-receiving section A is straight and closed, while its inner longitudinal portion is open, and the edges 12 are inclined from the top downward relatively to the edge portion 11 in a manner to render the lower portion of the said section wider. At each inclined edge 12 an outwardly-extending marginal flange 13 is formed. The said section A is 45 provided with a top 14, that extends beyond the inclined edges 12 and at its projected portion is provided with a downwardly-extending guide-lip 15^a, and at the outer straight edge 11 of said section A an aperture 15 is 50 provided, through which the shank 16^a of a pin C is passed and likewise through a corre-

sponding aperture 17 in the bottom section 16 of said section.

The section B, containing the locking mechanism, is of uniform diameter throughout its length and is mounted to slide upon the pin-receiving section A at its inclined edges, being to that end provided at the edges of its inner longitudinal portion, which is open, with inwardly-extending flanges 18, 60 65 that engage with the flanges 13 of the section A, as shown in Fig. 3, whereby to prevent transverse separation of the sections when assembled.

The bottom of the section B is open; but 70 its top is partially or entirely closed by a horizontal lip 19, and in the normal position of the said sections A and B the lip 19 of the section B lies close to the top 14 of the section A, and the lip 15^a of the latter section 75 is in engagement with the outer surface of the section B, as is shown in Fig. 2.

A spring 21, preferably a coiled spring, is located within the section B, having bearing at its lower end upon the bottom of the section A and griding contact with the inclined edges of said section A, which spring at its upper end supports a ball 22, holding said ball normally close to the lip 19 of the section B, as is also shown in Fig. 2. The ball 22 engages with the inclined edges of the section A, and when said ball is in its upper or normal position it also so engages with the shank 16^a of the pin C that when an attempt is made to withdraw the pin from the device 90 without properly operating its sections such an attempt will tend only to bind the device closer to the pin. When, however, a separation is desired, it is simply necessary to draw down the section B, whereupon the ball travels down the inclined edges of the section A, as is shown in dotted lines in Fig. 2 and in full lines in Fig. 4, and is carried away from the shank of the pin C, and the latter at such time may be quickly and conveniently withdrawn from the device. When the section B is released, it returns to its normal position, and the device is again in condition for locking engagement with a pin.

105 The pin-carrying section A may be properly termed the "body-section" and the sliding section B a "locking-section."

Having thus described my invention, I claim as new and desire to secure by Letters Patent—

110 A pin-retaining device, consisting of a body-section substantially U-shaped in cross-

section, having a closed top and bottom and registering openings therein for the passage of a pin, the longitudinal edges at the open portion of the said body-section being downwardly and outwardly inclined, a locking-section mounted to slide upon the body-section at its inclined portion, said locking-section being also substantially U-shaped in cross-section, its outer longitudinal edge portion being its closed portion and said locking-section being provided with an open bottom and a substantially closed top, the top of the locking-section being below the top of the body-section, a guide-lip extending down from the top of the body-section in engagement with the outer edge portion of the locking-section, a ball located within the locking-section, adapted to travel upon the inclined

edges of the body-section, which ball when in the upper portion of the locking-section 20 being in position for engagement with a pin passed through the apertures in the body-section, and a spring upon which said ball rests, the lower end of the said spring bearing upon the bottom of the body-section, and 25 an inner side portion of said spring having bearing upon the inclined edges of the body-section, for the purpose described.

In testimony whereof I have signed my name to this specification in the presence of 30 two subscribing witnesses.

ROBERT FISCHER.
